(57) **CLAIM**

The ornamental design for a stethoscope chestpiece, as shown and described.

DESCRIPTION

FIG. 1 is a bottom, left, first end perspective view of the stethoscope chestpiece.

FIG. 2 is a top, left, first end perspective view of the design of FIG. 1;

FIG. 3 is a second end view of the design of FIG. 1;

FIG. 4 is a first end view of the design of FIG. 1;

FIG. 5 is a right side view of the design of FIG. 1, the left side being a mirror image thereof;

FIG. 6 is a top view of the design of FIG. 1; and,

FIG. 7 is a bottom view of the design of FIG. 1.

The broken lines represent unclaimed portions of the stethoscope chestpiece.

1 Claim, 4 Drawing Sheets
